Thomas A. Prus, Strathclair, Manitoba, Canada

Application September 2, 1952, Serial No. 21,278

Term of patent 7 years

(Cl. D44—22)

To all whom it may concern:

Be it known that I, Thomas A. Prus, a citizen of Canada, residing at the town of Strathclair, in the Province of Manitoba, Canada, have invented a new, original, and ornamental Design for a Combined Pepper-and-Salt Shaker, of which the following is the specification, reference being had to the accompanying drawings, forming part thereof.

Figure 1 is a perspective view of the combined pepper and salt shaker illustrating my new design.

Figure 2 is a plan view of the shaker shown in Figure 1.

The end opposite that shown in Figure 1 is substantially the same as the one shown.

I claim:

The ornamental design for a combined pepper-and-salt shaker substantially as shown and described.

THOMAS A. PRUS.
